UNITED STATES PATENT OFFICE

ALFRED B. LAWTHER, OF CHICAGO, ILLINOIS.

IMPROVEMENT IN OLEAGINOUS-SEED CRUSHERS.

Specification forming part of Letters Patent No. 222,591, dated December 16, 1879; application filed November 7, 1879.

To all whom it may concern:

Be it known that I, ALFRED B. LAWTHER, of Chicago, in the county of Cook and State of Illinois, have invented certain Improvements in Machines for Crushing Oleaginous Seeds, of which the following is a specification.

This invention relates to a machine for crushing oleaginous seeds of the general character shown and described in Letters Patent No. 180,770, dated August 8, 1876, consisting of crushing-rolls mounted in vertical frames and driven by power and friction alternately. In using machines so constructed, in which part of the rolls are driven by power and part by friction from the power-driven rolls, I have found that the rolls driven by friction of two adjacent rolls, one above and one below, tend, as they are momentarily controlled by one or other of the driving-rolls, to vibrate laterally to the extent of any looseness in the bearings. This vibration, in addition to causing an unpleasant noise, which is sufficient at times to interfere with the comfort of people in the factory, also rapidly wears the bearing-surfaces. This wear, in turn, increases the vibration, thus rendering frequent repairs necessary.

To remedy this defect is the object of the present invention, and I accomplish it by mounting the rolls one above the other in such manner that the axes of the alternate rolls do not lie in the same vertical plane, the effect being to produce a wedging action between the rolls, which has a tendency to keep each alternate roll in opposite directions close to the frames in which they are placed. Unavoidable wear in such a structure, instead of increasing the vibration, will rather tend to increase the wedging action, thus effectually preventing any vibration, rendering repairs of less urgency.

In the accompanying drawings, which form a part of this specification, is shown at Figure 1 a front view of a set of rolls of my improved construction, and at Fig. 2 an end view of the same.

In the example shown three rolls are given

as being sufficient number to represent the principle of the invention; but it will be understood that any number of rolls may be employed which is found desirable.

In the said drawings, A represents one of the rolls, which is driven by power, which may be applied to a band-wheel upon its axis. A' A² are the alternate rolls, one above and the other below the power-driven roll, and driven by friction from the latter. All of the rolls are journaled in sliding boxes B, mounted in an upright slideway, C, at each end of the rolls, so that the weight of the rolls will rest one upon the other.

It will be seen by reference to the drawings that the axes *a* of the rolls are so journaled in the boxes as that the power-driven roll is at one side, and the friction-driven roll at the other side, of the center, which produces the wedging action of the rolls above referred to.

The amount of divergence of the axes from a coincident line may, of course, be varied in the judgment of the constructor to suit the requirements of the particular service, diameter of rolls, and speed of revolution.

I find that with rolls twelve inches in diameter, revolving at a rate of one hundred and seventy-five to one hundred and eighty revolutions per minute, a divergence of the axes from a coincident vertical line of a quarter of an inch gives good results.

My invention may also be used with good effect where all the rolls are driven by power, as is sufficiently obvious.

I claim—

The combination of crushing-rolls mounted in an upright frame and resting one upon the other, and having their centers of motion alternately upon opposite sides of the central line, for the purpose of producing a wedging action between the rolls to obviate vibration, substantially as specified.

ALFRED B. LAWTHER.
